DESIGN FOR A BOTTLE

Laurence J. Colwell, New York, N. Y., assignor to Charles of the Ritz, Inc., New York, N. Y., a corporation of Delaware

Application December 17, 1940, Serial No. 97,403

Term of patent 14 years

To all whom it may concern:

Be it known that I, Laurence J. Colwell, a citizen of the United States, residing at New York, in the county of New York and State of New York, have invented a new, original, and ornamental Design for a Bottle, of which the following is a specification, reference being had to the accompanying drawing, forming part thereof.

In the drawing

Fig. 1 is a front elevational view of a bottle showing by new design;

Fig. 2 is a rear elevational view thereof.

Fig. 3 is a top plan view.

I claim:

The ornamental design for a bottle, as shown.

LAURENCE J. COLWELL.
